US0D1071375S

(12) **United States Design Patent** (10) **Patent No.:** **US D1,071,375 S**
(45) **Date of Patent:** **** Apr. 15, 2025**

(54) **KNEE PAD**

(71) Applicant: **Dimeng Chen**, Zhejiang (CN)

(72) Inventor: **Dimeng Chen**, Zhejiang (CN)

(73) Assignee: **NINGBO KAIXIN PROTECTIVE PRODUCTS CO., LTD**, Zhejiang (CN)

(**) Term: **15 Years**

(21) Appl. No.: **29/870,272**

(22) Filed: **Jan. 19, 2023**

(51) LOC (15) Cl. **02-99**

(52) U.S. Cl.

USPC **D29/121.1**

(57) **CLAIM**

The ornamental design for a knee pad, as shown and described.

DESCRIPTION

FIG. 1 is a front and top perspective view of a knee pad, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the knee pad that form no part of the claimed design.

1 Claim, 8 Drawing Sheets
